UNITED STATES PATENT OFFICE.

HENRY G. THOMPSON, OF NEW HAVEN, CONNECTICUT, ASSIGNOR TO THE NEW HAVEN NOVELTY MACHINE COMPANY, OF SAME PLACE.

DESIGN FOR A PIPE-CO尤PLING.

SPECIFICATION forming part of Design No. 33,225, dated September 18, 1900.

Application filed August 17, 1900. Serial No. 27,214. Term of patent 14 years.

To all whom it may concern:

Be it known that I, HENRY G. THOMPSON, a citizen of the United States, residing at New Haven, county of New Haven, and State of Connecticut, have invented and produced a new, useful, and original Design for a Pipe-Coupling, of which the following is a specification, reference being had to the accompanying drawings, forming a part thereof.

Figure 1 of the drawings shows in side elevation a pipe-coupling illustrating my design, and Fig. 2 is a right-hand end view thereof.

The leading feature of my design for a pipe-coupling consists in an elongated tubular body having a series of peripheral grooves at one end and at its other end a peripherally-grooved circular enlargement or flange having a tapering projection extended from its outer face in axial alignment with the body.

The tubular elongated body f has at one end a series of peripheral grooves f' , and at its other end the body has a circular enlargement or flange f^2 , peripherally grooved, as at f^3 , and a tapering projection f^4 extends from the outer face of the enlargement in axial alignment with the body. 25

Having fully described my design, what I claim as new, and desire to secure by Letters Patent, is—

The design for a pipe-coupling substantially as herein shown and described. 30

In testimony whereof I have signed my name to this specification in the presence of two subscribing witnesses.

HENRY G. THOMPSON.

Witnesses:

H. GRANT THOMPSON,
GEORGE E. HAIGHT.
